(57) **CLAIM**

The ornamental design for a toy bow, as shown and described.

DESCRIPTION

FIG. 1 is a perspective view of the toy bow showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 1;

FIG. 11 is an enlarged view of a portion indicated with numeric 11 in FIG. 1;

FIG. 12 is an enlarged view of a portion indicated with numeric 12 in FIG. 1;

FIG. 13 is an enlarged view of a portion indicated with numeric 13 in FIG. 2; and,

FIG. 14 is an enlarged view of a portion indicated with numeric 14 in FIG. 2.

The evenly spaced broken lines shown in the drawings are included for the purpose of illustrating portions of the toy bow that form no part of the claimed design; the unevenly spaced broken lines delineate enlarged areas of the figures and form no part of the claimed design.

1 Claim, 14 Drawing Sheets
